Attorney

UNITED STATES PATENT OFFICE.

WALTER WESLIE GRAMER, OF MARINETTE, WISCONSIN.

TESTING APPARATUS.

1,349,831.

Specification of Letters Patent. Patented Aug. 17, 1920.

Application filed March 8, 1919. Serial No. 281,567.

To all whom it may concern:

Be it known that I, WALTER W. GRAMER, a citizen of the United States, residing at Marinette, in the county of Marinette and State of Wisconsin, have invented certain new and useful Improvements in Testing Apparatus, of which the following is a specification, reference being had to the accompanying drawings.

This invention relates to certain improvements in testing apparatus, and has relation more particularly to a device of this general character especially designed and adapted for use in connection with the ignition system of an internal combustion engine, and it is an object of the invention to provide a novel and improved apparatus of this general character whereby it may be readily determined which of the plugs may be faulty or dead and which also operates to determine trouble in the coil.

Another object of the invention is to provide a novel and improved apparatus of this general character comprising normally closed circuit breakers interposed in the wires leading from the coil to the plugs and each of which circuit breakers is operable independently of the other, together with spaced terminals forming a spark gap coacting with each of the circuit breakers, whereby the same may be placed in electrical connection with the coil when the circuit to a plug is broken.

The invention consists in the details of construction and in the combination and arrangement of the several parts of my improved testing apparatus, whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in front elevation of a testing apparatus constructed in accordance with an embodiment of my invention.

Fig. 2 is a view in rear elevation of the device as herein embodied, with a portion broken away.

Fig. 3 is a sectional view taken substantially on the line 3—3 of Fig. 1, and

Fig. 4 is a fragmentary longitudinal view taken substantially on the line 4—4 of Fig. 3.

As disclosed in the accompanying drawings, H denotes a housing having disposed through a side wall 1 thereof a plurality of binding posts P adapted for electrical connection through the medium of the conductors or wires a with a coil box (not shown) preferably of the type employed in connection with the ignition system of the Ford automobile. Also disposed through this wall 1 is a second series of binding posts P' adapted for electrical connection through the medium of the conductors or wires b with the spark plugs (not shown) of the motor proper. Arranged within the housing H is a shelf 2 having secured thereto the base members 3 in electrical connection with the posts P through the medium of the conductors or wires c and the securing members 4 for said base members 3.

Pivottally engaged and in electrical connection with each of the base members 3 is a switch S. This switch comprises a pair of spring jaws which normally engage the opposite faces of the flattened extension 5 of a post P' extending within the housing H, so that direct electrical connection is normally maintained between the coil and a spark plug.

Extending between the jaws of each of the switches S is an end portion of a plug A having rectilinear movement through the second side wall 6 of the housing H. The portion of the plug A arranged between the spring jaws of the switch is pivotally engaged therewith, as indicated at 7, so that upon imparting endwise movement to the plug A, the switch S will be engaged with or disengaged from an extension 5 of post P'. When the post is inwardly disposed, the switch S is in engagement with an extension 5. To facilitate the desired manipulation of the plug A, the outer end portion thereof is provided with a button 8 or the like.

The outer face of the side wall 6, below each of the plugs A, is provided with a recess or pocket 9 in which extends a pair of spaced terminals 10 and 10^a forming a spark gap. The terminal 10 extends within the housing H, as indicated at 11, so that when a plug A is moved outwardly or withdrawn, the coacting switch will have electrical engagement therewith.

All of the terminals 10^a are connected in

- series and with a post P'' depending from the bottom of the housing H . The post P'' is adapted to be suitably grounded through the medium of a conductor or wire a .
- 5 The extensions 5 of the post P' and the portions 11 of the terminals 10 constitute contact members and, as hereinbefore stated, the switches S are normally in engagement with the extensions or contacts 5.
- 10 In the event of engine trouble, upon pulling out a plug A to cause the coacting switch to engage a contact 11, the plug connected with the concomitant post P will be cut out and a spark will be created between the terminals 10 and 10^a under control of such switch. If the spark thus created is thin and streamy, it will indicate that the trouble is in the distributor or coils or the conductor or wire a leading therefrom. If 15 the spark should be good and when the plug A is pushed inwardly to engage the contact 5, and the coacting cylinder of the motor does not fire, the trouble is with the spark plug or the valves are not closing.
- 20 By pulling out three plugs A , resulting in the motor running on one cylinder, a thorough test is made of that cylinder while the sparks of the remaining cylinders may be determined. Each cylinder may, in turn, 25 be tested in this manner.
- 25 From the foregoing description, it is thought to be obvious that a testing apparatus constructed in accordance with my invention is particularly well adapted for use 30 by reason of the convenience and facility with which it may be assembled and operated and it will also be obvious that my invention is susceptible of some change and modification without departing from the 35 principles and spirit thereof and for this reason I do not wish to be understood as limiting myself to the precise arrangement and formation of the several parts herein shown in carrying out my invention in 40 practice except as hereinafter claimed.
- 45 I claim:
1. A spark testing apparatus including a housing provided with an opening in one of its walls, a pair of spaced terminals extending within said opening and forming a spark gap, one of said terminals being grounded and the second of said terminals extending within the housing to provide contact, a pair of contacts carried by the second wall of the housing, adapted to be 50 interposed in a line leading from a coil to a plug, a movable contact member supported within the housing and in electrical connection with one of the last named contacts, said movable contact, when in one position, 55 engaging the second of the last named contacts, and when in a second position contacting with the first named contact, and a member engaged with the movable contact and extending exteriorly of the housing for 60 imparting movement to the movable contact member, said movable contact member comprising a pair of spring jaws having similar ends pivotally engaged within the housing, the contacts with which said spring 65 jaws coact being received between said jaws.
- 65 In testimony whereof I hereunto affix my signature in the presence of two witnesses.
- WALTER WESLIE GRAMER.
- Witnesses:
- LAWRENCE BUNDY,
MIKE SETUNSKY.
